Primary Examiner — Cynthia Underwood(74) *Attorney, Agent, or Firm* — Margaret Polson; Polson Intellectual Property Law, PC(57) **CLAIM**

The ornamental design for a carabiner with hex wrench, as shown and described.

DESCRIPTION

FIG. 1 is a top side plan view of my new design for a carabiner with hex wrench.

FIG. 2 is a back side elevation view of FIG. 1.

FIG. 3 is a front side elevation view of FIG. 1.

FIG. 4 is a right side elevation view of FIG. 1.

FIG. 5 is a left side elevation view of FIG. 1.

FIG. 6 is a bottom side plan view of FIG. 1; and,

FIG. 7 is a front side perspective view of FIG. 1.

The broken lines in the drawings depict environmental subject matter/or parts of the carabiner with hex wrench only and form no part of the claimed design.

1 Claim, 2 Drawing Sheets(56)
